A. Whitman

United States Patent Office.

R. H. SIPES, OF BLOODY RUN, PENNSYLVANIA.

Letters Patent No. 96,154, dated October 26, 1869.

IMPROVED WASHING-MACHINE.

The Schedule referred to in these Letters Patent and making part of the same.

To all whom it may concern:

Be it known that I, R. H. SIPES, of Bloody Run, in the county of Bedford, and in the State of Pennsylvania, have invented a new and useful Improvement in Gum Clothes-Washing Machines; and do hereby declare that the following description, taken in connection with the accompanying plate of drawings, hereinafter referred to, forms a full and exact specification of the same, wherein I have set forth the nature and principles of my said improvement, by which my invention may be distinguished from others of a similar class, together with such parts as I claim, and desire to secure by Letters Patent.

My invention relates to that class of washing-machines in which fluted rollers, operated by a crank, are made use of, and consists in the combination and arrangement of the parts thereof, as hereinafter described.

In the accompanying plate of drawings, which illustrate my invention, and form a part of the specification thereof—

Figure 1 is a perspective view, and

Figure 2, a vertical transverse section.

In both of the figures, corresponding parts are represented by similar letters.

The construction, operation, and relative arrangement of the component parts of my invention are as follows, to wit:

The wooden prism A is enveloped by the peripheral gum covering B, fluted with longitudinal furrows, and is operated by the crank c, attached to the shaft D.

The said shaft has its bearings in the bottom of elongated quadrilateral apertures or vertical slits E, cut in the cheeks or side-pieces F.

About the ends of the said shaft is the ring G, supporting the pendent hook H, which engages with another hook at the end of the rod I.

The other end of the said rod is coiled to form a spiral spring about the knobs or spindles K at the ends of the cross-bar L.

The rubber bar M is fluted with longitudinal fur-

rows upon its upper side, and covered with zinc. The said bar is secured in position by means of slots prepared for the reception of the ends thereof in the cheeks or side-pieces F.

On each side of the said bar are the small fluted rollers N, the office of which is merely to serve as conductors for the clothing to be washed.

Attached to the bottom of the frame are the hooks o with sharpened points, and the elbow-screw and thumb-nut P, working in the quadrangular slot R.

The operation of my invention is as follows, to wit:

The machine having been fastened to the tub, by means of the hooks o and screw P, rotary motion is imparted to the fluted roller B, by means of the crank c, causing the ribs of the same to engage with the zinc-covered ribs of the cross or rubber bar M. The clothing to be cleansed having been passed over the rollers N, is seized by the gum roller B, and pressed against the bar M, the action of the said appliances being similar to that of the hand upon a common wash-board. The spiral spring upon the spindle K, connected, as aforesaid, with the journal of the said roller B, allows the same to ascend, as may be requisite, in order to permit the clothes to pass under it, but causes a constant pressure to be exercised upon them.

When not in use, the rod I may be disengaged from the hook H, thereby preventing the said spring from becoming weakened by tension.

Having thus described the nature, construction, and operation of my invention, I will proceed to designate what I claim, and desire to secure by Letters Patent, in the following clause:

I claim fluted roller-crank c, small rollers N, spring K, pendent hook H, cheeks F, hooks o, slits E, and screw P, when combined and arranged as described.

In testimony that I claim the foregoing, I have hereunto set my hand, this 16th day of September, 1869.

R. H. SIPES.
